UNITED STATES PATENT OFFICE.

JOSEPH M. BOUSQUET, OF MIDDLESEX, VERMONT.

MOISTENER.

1,369,384.

Specification of Letters Patent. Patented Feb. 22, 1921.

Application filed March 16, 1920. Serial No. 366,324.

To all whom it may concern:

Be it known that I, JOSEPH M. BOUSQUET, a citizen of the United States, residing at Middlesex, in the county of Washington 5 and State of Vermont, have invented certain new and useful Improvements in Moisteners, of which the following is a specification, reference being had therein to the accompanying drawing.

10 This invention relates to a device for moistening stamps, envelop-flaps, and other articles or parts coated with adhesive, in order to render the adhesive susceptible of performing the function for which it is intended.

15 It is an object of the invention to provide a simple and efficient device for that purpose, with comparatively few parts assembled in such manner that the device will not easily get out of order, and with the parts so arranged that the moistening operation may be performed easily and quickly.

Another object of the invention is to combine with such a device means whereby a 20 moistened adhesive-coated part may be pressed against the surface to which it adheres, and so to arrange the presser that it also may be used as a blotter.

A further purpose of the invention is so 25 to form the pressing means that blotting-paper or other sheet material may be placed easily therein and removed therefrom.

When read in connection with the description herein, the characteristics of the 30 invention will be apparent from the accompanying drawing, forming part hereof, wherein an embodiment of the invention is disclosed, for purposes of illustration.

While the disclosures herein exemplify 35 what now is considered to be a preferable embodiment of the invention, it is to be understood that it is not the intention to be limited necessarily thereto in interpretation of the claims, as modifications and adaptations within the limits of the claims can be made without departing from the nature and spirit of the invention.

Like reference-characters refer to corresponding parts in the views of the drawings, of which—

Figure 1 is a front elevation;

Fig. 2 is a rear elevation;

Fig. 3 is a perpendicular transverse sectional view; and

Fig. 4 is a bottom view of the upper member.

Having more particular reference to the drawing, 5 designates a somewhat elongated base, or lower member constituting a support for the device. The base has a substantially flat upper surface; along one of the longer side portions the material of the base extends slightly above the plane of that surface as a rib 6, and in the rib there is a groove 7 opening to the flat surface. The 60 groove is arranged to receive and hold a marginal portion of a sheet of blotting-paper or other suitable absorptive material 8 resting on the upper surface of the base. If desired, a sheet of felt or other suitable 65 soft material 9 may be placed under the sheet 8.

A flat spring 10 is secured to the side of the base opposite to the rib 6 and it extends upwardly therefrom. The spring is secured 70 to the side of and constitutes a support for an upper member 11. The member 11 has a substantially flat bottom surface of about the area of the upper surface of the base 5, and in its marginal portions it has grooves 80 12 arranged to receive and to hold upturned edges of a piece of blotting-paper or other suitable absorptive material 13. If desired, a sheet of felt or other suitable soft material 14 may be interposed between the sheet 13 85 and the surface of the member 11. The absorptive sheets may be withdrawn by pulling them from the holding-grooves and replaced by new ones.

The spring 10 is tensioned to hold the 90 absorptive coverings of the base 5, and upper member 11 normally separated and to permit them to be brought together when the upper member is pressed downwardly, so that a stamp-bearing sheet, the closed 95 moistened flap of an envelop, a sheet bearing writing to be blotted, or other article or part of sheet material to be pressed may be placed therebetween and subjected to pressure when the upper member is moved 100 thereagainst. When pressure on the upper member is released, the spring, of course, will return it to normal position and permit withdrawal of the pressed article or part.

A well 15, open at the top, is located centrally of the upper member 11, and that member may be weighted by being formed in solid mass on each side of the well. The upper surface of that member is inclined downwardly from each side of the well. 110 Opposite walls of the well have alined seats 16, which loosely and removably hold trun-

nions 17 of a lower roller 18, which is rotatable in water in the well.

A standard 19 is secured to a side of the upper member, preferably against the 5 spring 10 and by the same fastenings 20 as hold that member 11 on the spring. A cross piece 21 of the standard 19 extends over the lower roller 18, and it has at its free end a depending lug 22. Alined vertical slots 23 10 in the standard and lug hold and act as guides for trunnions 24 of an upper roller 25 and permit that roller to rest on the lower roller 18.

It will be seen that the arrangement is 15 such that pieces of sheet material, or an article of that material, may be passed easily between the rollers, and that the surface thereof in contact with the lower roller rotating in water in the well will be moistened. The inclined upper surfaces of the 20 upper member 11 serve to guide the article between the rollers. If it is desired to press the moistened article or part, as when affixing a stamp or closing an envelop-flap, the 25 article is placed between the coactive surfaces of the base and upper member and the latter member then is pressed downwardly thereagainst. The cross piece 21 is comparatively broad and rounded on top, and thus 30 it is adapted to have a hand placed thereon to press the upper member downwardly.

Having thus described my invention, what I claim as new, and desire to secure by Letters Patent, is—

35 1. A device of the kind described comprising the combination of a lower member having a substantially flat upper surface, an upper member containing a well open at the top and having a substantially flat lower 40 surface arranged to coact with said surface of the lower member, a lower roller in said well, a spring keeping said surfaces normally out of contact, a standard on said upper member, and an upper roller on said 45 standard bearing against said lower roller.

2. A device of the kind described comprising the combination of a lower member having a substantially flat upper surface, an upper member containing a well open at the top and having a substantially flat lower 50 surface arranged to coact with said surface of the lower member, a lower roller in said well, a spring keeping said surfaces out of contact, a standard on said upper member having a cross piece arranged to be pressed 55 downwardly by a hand, and an upper roller carried by said standard and cross piece bearing against said lower roller.

3. A device of the kind described comprising the combination of a lower member 60 having a substantially flat upper surface, an upper member containing a well open at the top and having a substantially flat lower surface arranged to coact with said surface of the lower member, a lower roller in said 65 well, a spring keeping said surfaces normally out of contact, a standard on said upper member having a cross piece formed with a depending lug at its free end, there being alined vertical slots in said lug and stand- 70 ard, and an upper roller bearing against said lower roller and having trunnions loosely seated in said slots.

4. A device of the kind described comprising the combination of a base having a 75 substantially flat upper surface, an upper member containing a well open at the top and having a substantially flat lower surface arranged to coact with said surface of the base, a lower roller in said well, a flat 80 spring secured to said base, a standard, fastening means securing both said spring and standard to said upper member, the spring being tensioned to keep said coactive surfaces normally out of contact, and an 85 upper roller on said standard bearing against said lower roller.

In testimony whereof I affix my signature.

JOSEPH M. BOUSQUET.
